UNITED STATES PATENT OFFICE.

WILLIAM H. NICHOLLS, OF BROOKLYN, NEW YORK.

MOLDING MACHINE.

Application filed June 20, 1925. Serial No. 38,501.

This invention relates to improvements in apparatus for forming molds and has for its general object the provision of a simple and inexpensive machine for jolting or jarring 5 the sand in a flask or flask member and then squeezing or compressing the sand about the pattern.

Another object of the invention is to mount the jolting and squeezing mechanism 10 and the upper pressure head on a vertical tubular support, said support forming a large air reservoir from which air is taken to operate the jolting and squeezing mechanism.

Another object of the invention is to mount the jolting and squeezing mechanism and the upper pressure head so that they 15 will be vertically and rotatively adjustable on the vertical tubular support.

Other objects and advantages of the invention will appear hereinafter.

In the drawings:

Figure 1 is a front elevation of the machine;

Fig. 2 a vertical central sectional view thereof, parts being shown in side elevation;

Fig. 3 a horizontal sectional view taken on the line 3-3 of Fig. 1;

Fig. 4 a view similar to Fig. 3, taken on the line 4-4 of Fig. 1;

Fig. 5 a detail perspective view of the clamping ring which sustains the upper pressure head in position; and

Fig. 6 a detail perspective view of the upper pressure head.

Referring to the various parts by numerals, 1 designates a tubular cylindrical standard which is closed at its upper end by a cap 2 and at its lower end by a cap 3 said 40 caps converting the tubular standard into an air tight reservoir. The standard is preferably of considerable diameter in order that it may contain a considerable body of air under pressure, as will be hereinafter described. The lower end of the standard is 45 preferably embedded in concrete. Of course, the standard may be secured in a vertical position in any suitable manner. The base 4, which carries the jolting and squeezing pistons and the air control valve, is clamped to the standard 1 and is vertically and rotatively adjustable thereon. At one end the base is formed with a semi-cylindrical vertical socket 5 adapted to receive the cylindrical standard; and a semi-cylindrical clamp member 6 secures the base to the

standard. The clamp member is formed with vertical side flanges 7 through which bolts 8 pass. These bolts also pass through the corresponding flanges 9 formed on the base member of the clamp. The base may be clamped at any desired height on the standard and in any desired radial position with respect to the standard. The clamp 6 will hold the base in any desired adjusted position on the standard. The base is preferably a hollow cylinder open at its upper end and closed at its lower end. A large hollow main squeeze piston 10 is adapted to reciprocate vertically in the cylindrical base; and said piston is formed with a small central cylinder 11 which is open at its upper end. The piston 10 normally rests on the bottom wall of the cylinder base, its upper end projecting slightly above the base as shown 75 clearly in Fig. 2. In the wall of the cylinder 11, a short distance above the bottom of said cylinder, is formed an exhaust opening 12 which leads into the interior of the piston 10, and thence to atmosphere, through apertures in the upper wall of said piston. A small jolt piston 13 is adapted to reciprocate 80 vertically in the cylinder 11 relatively to the main piston 10. The jolt piston carries at its upper end a pressure head and flask support 14. This pressure head is shown as rectangular in plan view and extends outwardly beyond the cylindrical portion of the base. When the jolt piston is in its lowermost position the pressure head 14 rests directly on the upper surface of the main piston 10. The lower end of the jolt piston is open and at a short distance upwardly from said lower end it is provided with a cross wall 15. Within the jolt piston is arranged 90 an air pipe 16 whose lower open end extends through the cross wall 15 and whose upper end extends outwardly through the side of the pressure head and flask support 14. An air supply pipe 17 enters the main cylinder 100 through the bottom wall thereof and delivers air into said cylinder below the piston 10. The air supply pipe 16 and 17 lead to an air control valve 18 which is supported on the base 4. A main air supply pipe 19 is connected to the interior of the tubular standard 1 through the upper cap 2. The lower part of the standard is connected to the air valve through an air pipe 20 so that air for the operation of the jolting and squeezing 110 mechanism will be taken from the tubular standard. This provides a large volume of

air directly adjacent the jolting and squeezing mechanism so that the air pressure for the operation of this mechanism will be maintained nearly uniform during the operations of the machine. It has been found that where the air for operating the jolting and squeezing mechanism is supplied through a small pipe a great variation in air pressure results. By drawing the air from a comparatively large reservoir adjacent the molding machine much more uniform air pressures can be maintained at the apparatus.

The pressure head 14 is held against rotation and is guided in its vertical movement by a guide rod 21 which extends through and reciprocates in a vertical aperture in the base. This rod is provided with an adjustable stop collar 22 at its lower end which is adapted to engage the base to limit the upward movement of the pressure head in the mold squeezing operation. The stop collar preferably moves up into a vertical channel formed in the base and engages the upper wall of said channel to limit the upward movement of the pressure head. It is manifest that the base and all the parts carried thereby may be adjusted vertically on the standard and horizontally around the standard without disturbing the operative relation of the parts. The valve 18 may be of any suitable construction but I prefer to use a single rotary valve such as that shown and described in my Patents No. 1,277,745, dated September 3, 1918, and 1,472,807 dated November 6, 1923. This single valve controls the supply of air to the jolt piston and also to the squeeze piston, as will be hereinafter described. The pipe 20 is preferably flexible and of sufficient length to permit of any desired adjustment of the base on the standard 1.

The upper pressure head 23 is formed at one end with a tubular sleeve-like socket 24 adapted to fit the tubular standard. This socket is cut out horizontally to form upper and lower members having a space between them. To sustain the upper pressure head on the tubular standard and to resist upward pressure thereon I provide a clamp ring 25 which encircles the standard and fits between the upper and lower members of the socket 24. The clamp ring is provided with two outwardly extending flanges 26 through which clamping bolts 27 extend, said bolts clamping said ring rigidly to the standard between the upper and lower members of the socket 24. The socket 24 fits comparatively loosely around the standard so that the upper pressure head may be freely swung laterally and rotated about the standard in order to remove it from its normal position directly over the pressure head 14. To limit the horizontal free rotative movement of the upper pressure head the

clamp ring 25 is provided with two stop lugs 28 and 29. The upper pressure head is provided with two vertical stop flanges 30 and 31 which are adapted to engage the stops 28 and 29 of the clamp ring. These stops are so arranged that when the stop flange 30 is in engagement with the stop lug 28 the upper pressure head is directly over the lower pressure head 14, as shown in Fig. 3. The stop 29 is so located on the clamp ring that when the upper pressure head is rotated on the standard to the position shown in dotted lines in Fig. 4 the said stop lug will be engaged by the stop flange 31. The clamp ring is adjustable around the standard to secure the correct positions for the stop lugs 28 and 29 and, of course, said stop lugs must be properly located with respect to the lower pressure head 14. The upper pressure head is formed with a central vertical strengthening web 32 in the outer end of which is formed a hand-hole 33 for the convenient manipulation of the head.

The tubular standard 1 is provided near its lower end with a drainage cock 34 by means of which any accumulated water may be drained from the reservoir, said cock being preferably located below the connection of air pipe 20.

To form a mold the flask and pattern are placed on the head 14 and the flask is then filled with sand. The valve handle is then turned to permit air to flow from the reservoir formed by the standard 1 through pipe 16 into the small cylinder 11 below the wall 15 of the jolt piston. The piston 13 and the head 14 will thus be elevated slightly until the exhaust port 12 is uncovered whereupon the piston and the head will drop down to the upper end of the main squeeze piston, this operation being repeated in rapid succession as long as the control valve is held in the position indicated. The sand in the mold frame is thus jarred and evenly packed therein around the pattern. The sand is then struck off level with the top of the flask and the usual squeeze board placed in position. The handle of the air control valve is then turned to admit air to pipe 17 and below the main squeeze piston 10. This forces the squeeze piston and the head 14 upwardly, forcing the squeezing board into engagement with the upper pressure head 23. After the mold is squeezed the squeeze piston may be lowered and the upper pressure head swung to one side so that the mold may be conveniently removed from the head 14.

In setting up the machine the base is adjusted on the vertical standard to the proper height for convenient operation and is also adjusted rotatively on the standard to bring the mechanism to the right position. The upper pressure head is then mounted on the standard and adjusted to bring it into proper

co-operative relation with the jolting and squeezing mechanism. The cap 2 and the main air supply pipe are then connected to the top of the tubular standard. The large volume of air within the standard prevents any sudden material drop in air pressure during the operation of the machine.

What I claim is:

1. A molding machine comprising a vertical, cylindrical tubular standard forming an air reservoir, a mold jolting and squeezing mechanism vertically and rotatively adjustable on said standard, an air control valve carried by said jolting and squeezing mechanism and controlling the supply of air to said mechanism, an upper pressure head rotatively mounted on the said standard above the jolting and squeezing mechanism, vertically adjustable means for sustaining said upper pressure head on said standard, said sustaining means being rotatively adjustable on said standard and carrying stop lugs adapted to be engaged by stop flanges on the pressure head to limit the rotative movement of the upper pressure head in both directions about the tubular standard, a main air supply pipe connected to the tubular standard, and an air pipe connected to the tubular standard and to the air control valve.

2. A molding machine comprising a vertical, cylindrical tubular standard forming an air reservoir, a mold squeezing mechanism vertically and rotatively adjustable on said standard, an air control valve carried by said squeezing mechanism and controlling the supply of air to said mechanism, an upper pressure head rotatively mounted on the said standard above the squeezing mechanism, vertically adjustable means for sustaining said upper pressure head on said standard, said sustaining means being rotatively adjustable on said standard and carrying stop lugs adapted to be engaged by the pressure head to limit the rotative movement of the upper pressure head in both directions about the tubular standard, a main air supply pipe connected to the tubular standard, and an air pipe connected to the tubular standard and to the air control valve.

3. A molding machine comprising a vertical tubular standard forming an air reservoir, a mold forming mechanism vertically adjustable on said standard, an air control valve controlling the supply of air to said mechanism, an upper pressure head rotatively mounted on the said standard above the mold forming mechanism, vertically adjustable means for sustaining said upper pressure head on said standard, said sustaining means carrying a stop lug adapted to be engaged by the pressure head to limit the rotative movement of the upper pressure head in one direction about the tubular standard, a main air supply pipe connected

to the tubular standard, and an air pipe connected to the tubular standard and to the air control valve.

4. A molding machine comprising a vertical, cylindrical standard, a mold jolting and squeezing mechanism vertically and rotatively adjustable on said standard, an air control valve carried by said jolting and squeezing mechanism and controlling the supply of air to said mechanism, an upper pressure head rotatively mounted on the said standard above the jolting and squeezing mechanism, vertically adjustable means for sustaining said upper pressure head on said standard, said sustaining means being rotatively adjustable on said standard and carrying stop lugs adapted to be engaged by the pressure head to limit the rotative movement of the upper pressure head in both directions about the standard, and an air supply pipe connected to the air control valve.

5. A molding machine comprising a vertical, cylindrical standard, a mold jolting and squeezing mechanism vertically and rotatively adjustable on said standard, an air control valve carried by said jolting and squeezing mechanism and controlling the supply of air to said mechanism, an upper pressure head rotatively mounted on the said standard above the jolting and squeezing mechanism, a vertically adjustable clamp ring for sustaining said upper pressure head on said standard and resisting upward pressure on said head, said clamp ring being rotatively adjustable on said standard and carrying stop lugs adapted to be engaged by the pressure head to limit the rotative movement of the upper pressure head in both directions about the standard, and an air supply pipe connected to the air control valve.

6. A molding machine comprising a vertical standard, a base, means carried at one end of the base and adapted to clamp the base to the standard, said clamping means and the base being vertically adjustable on the standard, a jolt piston and a squeeze piston carried by the base, a pressure head and flask support connected to the jolt piston and normally resting on the top of the squeeze piston, a guide rod connected to said pressure head and moving vertically in an aperture in the base, a stop carried by said rod to limit the upward movement of said head, an upper pressure head formed with a tubular socket at one end adapted to receive the standard and to permit the said upper head to rotate thereon, said pressure head extending radially from the standard, a clamping ring adapted to be secured around the standard and to sustain the upper pressure head and to resist upward pressure on said head, said clamping ring being rotatively adjustable on the standard, a stop lug carried by the clamping ring and adapted to be engaged by the pressure head to limit the free

- 1 rotative movement of said upper head in one direction about the standard, an air control valve carried by the base, and an air supply pipe connected to said control valve.
- 5 7. A molding machine comprising a vertical standard, a base vertically adjustable on said standard, an air-operated mold jolting and squeezing mechanism carried by said base and controlling the supply of air to the said jolting and squeezing mechanism, an upper pressure head rotatively mounted on the standard above the jolting and squeezing mechanism, vertically adjustable means for sustaining said upper pressure head on said standard, and means carried by the standard to be engaged by the pressure head to limit the rotative movement of the pressure head in one direction about the standard.
- 10 7. A molding machine comprising a vertical standard, a base vertically adjustable on said standard, an air-operated mold jolting and squeezing mechanism carried by said base and controlling the supply of air to the said jolting and squeezing mechanism, an upper pressure head rotatively mounted on the standard above the jolting and squeezing mechanism, vertically adjustable means for sustaining said upper pressure head on said standard, and means carried by the standard to be engaged by the pressure head to limit the rotative movement of the pressure head in one direction about the standard.
- 15 8. A molding machine comprising a vertical standard, a base vertically and rotatably adjustable on said standard, an air-operated mold jolting and squeezing mechanism carried by said base and controlling the supply of air to the said jolting and squeezing mechanism, an upper pressure head rotatively mounted on the standard above the jolting and squeezing mechanism, vertically adjustable means for sustaining said upper pressure head on said standard, and means carried by the standard to be engaged by the pressure head to limit the rotative movement of the pressure head in one direction about the standard.
